UNITED STATES PATENT OFFICE.

HENRY AYLMER, OF SHERBROOKE, CANADA.

DESIGN FOR A ROCK-DRILL BIT.

SPECIFICATION forming part of Design No. 34,214, dated March 12, 1901.

Application filed February 16, 1901. Serial No. 47,703. Term of patent 14 years.

To all whom it may concern:

Be it known that I, HENRY AYLMER, a subject of Her Majesty the Queen of Great Britain, residing at Sherbrooke, in the county of 5 Sherbrooke, in the Province of Quebec, Canada, have invented and produced a new and original Design for Rock-Drill Bits, of which the following is a specification, reference being had to the accompanying drawings, forming part thereof.

Figure 1 is a perspective view of my drill point or bit. Fig. 2 is a plan view of the same at the cutting edge.

As shown in the drawings, the leading or 15 material features of my design consist in a

lateral notch A in the stem B of the bit, and distinct blades C, D, E, and F, but merging one into the other toward the center of the flat surface or shoulder G.

Having described my invention, what I 20 claim as new, and desire to secure by Letters Patent, is—

The design for a rock-drill bit, as herein shown and described.

Signed at Sherbrooke, Canada, this 19th day 25 of November, 1900.

HENRY AYLMER.
